SAFETY LATCH FOR ELEVATORS

William Webster Wilson, Los Angeles, Calif.

Application August 9, 1946, Serial No. 689,496

3 Claims. (Cl. 294—102)

1

This invention relates to elevators employed in suspending members such as pipes or tubes in derricks and relates in particular to an improved latch for elevators.

It is an object of the invention to provide a center latch elevator having a rugged and effective latch and a simple lock for preventing inadvertent opening of the latch. My present invention is shown in conjunction with a center latch elevator of the character described in United States Patent No. 2,356,805, granted to me August 29, 1944.

It is an object of the invention to provide a combined latch and lock for pipe elevators having a single means of operation.

It is an object of the invention to provide an elevator latch of the character set forth in the preceding paragraph having a latch lever adapted to engage a latch lug and a lock lever mounted on the latch lever for engagement with a lock lug, this lock lever having a manually engageable portion by which the release of the lock and the release of the latch is accomplished.

A further object of the invention is to provide in a latch and lock combination of this character a simple cooperation of elements wherein the wall which supports the lock lug serves as a guard for the manually engageable handle of the lock lever.

Further objects and advantages of the invention will be brought out in the following part of the specification, wherein reference to specific details of construction are for the purpose of fully disclosing a preferred embodiment of the invention without limiting the scope thereof set forth in the appended claims.

Referring to the drawing, which is for illustrative purposes only,

Fig. 1 is a plan view of a preferred embodiment of my invention.

Fig. 2 is a front elevation corresponding to Fig. 1.

Fig. 3 is a fragmentary sectional view, taken as indicated by the line 3—3 of Fig. 2.

Fig. 4 is an enlarged perspective view of the latch lever.

Fig. 5 is a fragmentary isometric view showing the operative relationship of the latch lever, lock lever and lock lug.

The elevator shown in the drawing comprises a pipe encircling structure 9 adapted to be closed and latched around a pipe which is to be suspended or lifted. Herein the term "pipe" is inclusive of any object used in a well derrick or in a well having a portion adapted to be engaged by

2

the elevator whereby the lifting or suspension of such member is accomplished. In the form of the invention shown, the elevator comprises two cooperating parts 11 and 12 hinged together by means of a hinge pin 14 so as to be swingable from open position into the closed position in which the elevator is shown. The jaws 11 and 12 are formed with inner semi-cylindrical bore surfaces 15 and 16, defining an opening to receive the cylindrical parts, such as a pipe, which is to be lifted or suspended. The jaws 11 and 12 have respectively first and second free ends 17 and 18 which are brought into juxtaposition when the jaws are closed around a pipe. The first free end 17 has thereon a latch lug 19 having a face or shoulder 20 lying to the right of the median plane a—a of the elevator and being disposed on a plane b—b which crosses the plane a—a in the manner shown in Fig. 1.

20 The second free end 18 has lugs 21, 22, 23, and 24 projecting therefrom to support a hinge pin 25 on a vertical axis which is spaced from the hinge pin 14 a greater distance than the center of the face or shoulder 20 of the latch lug 19. A latch lever 26 is swingable on the hinge pin 25. This latch lever 26 has vertically spaced horizontal arms 27 and 28, the leftward ends of which swing upon the hinge pin 25, and a vertical bar portion 29 which connects the rightward ends of the arms 27 and 28 and provides between the arms 27 and 28 a latching shoulder 30 for engagement with the latching shoulder 20 of the latch lug 19. The leftward ends of the arms 27 and 28 are connected by a vertical bar 31 and, for rotating the latch lever 26 in counterclockwise direction, a spring 32 is placed around the intermediate portion of the pin 25, one end 33 of this spring 32 engaging a portion of the body or jaw 12, and the other end 34 of the spring 32 engaging the bar 31 of the latch lever 26. The spring 32 constantly urges the latch lever 26 into a position wherein the latch face 30 thereof will cooperate with the latch shoulder 20 of the lug 19 when the jaws 11 and 12 are in closed relation. A projection 34 on the lug 23 of the jaw 12 limits the clockwise rotation of the latch lever 26.

As shown in Fig. 4, the latch lever 26 has vertically spaced lugs 36 and 37 projecting from the front face thereof, these lugs having openings 38 to receive a pin 39 on which a lock lever 40 is swingable. This lock lever 40 is disposed near the rightward end of the latch lever 26 and upon the front face of the bar 29 thereof.

The lock lever 40 comprises a vertically elongated arcuate wall 41 with upper and lower ends

of walls 42 and 43 projecting therefrom toward the latch lever 26 to engage the pin 39. These end walls 42 and 43 are of the shape of circular segments, the radial edges of the top wall 42 being disposed at an angle of substantially 90 degrees and the lower end wall 43 having thereon a lug 44 to engage the bar 29 of the latch lever 26 and thereby limit the counterclockwise rotation of the lock lever by a spring 45 which has its coiled portion surrounding the pin 39, this spring 45 being relatively weaker than the spring 34'. The lock lever 40 includes a flat wall 47 which projects rightwardly from the arcuate wall 41 in substantially parallel relation to the front face of the bar 29 and in spaced relation thereto. This manually engageable portion 47 projects rightwardly beyond the rightward edge of the bar 29 so as to constitute a manually engageable handle which may be pulled forwardly as indicated by the arrow 48 of Fig. 3. A locking shoulder 50 of the upper end wall 42 and that portion of the arcuate wall 41 adjacent thereto comprises a latch dog or shoulder proper for engaging a lock lug 51 formed on a wall 52 which projects from the jaw member 11 above the handle portion 47 of the lock lever 40 so as to serve as a guard for the handle portion 47 of the lock lever 40, as well as for supporting the lock lug 51.

From an inspection of Fig. 1, it will be perceived that the latch lever 26 swings around a hinge pin 25 which is disposed with its axis at a greater distance from the axis of the hinge pin 14 than is the center of the face 20 of the latch lug 19. It is characteristic of this arrangement of latch lever 26 and latch lug 19 that forces applied to the jaws 11 and 12 tending to separate them will produce forces in the latch lever 26 and latch lug 19 tending to prevent their disengagement. As an additional precaution against the latch lever 26 being inadvertently rotated in clockwise direction around the hinge pin 25 so as to move the rightward portion of the latch lever 26 out of engagement with the latch lug 19, the lock lever 40 and the lock lug 51 are provided.

When the latch mechanism is in operative condition, as shown in Fig. 1, the engagement of the lock lever 40 with the lock lug 51 prevents clockwise rotation of the latch lever 26. However, the lock lever 40 is so arranged with relation to the latch lever 26 that a single manual operation will accomplish release of the lock lever 40 from engagement with the lock lug 51 and clockwise rotation of the latch lever 26 so as to swing the same out of engagement with the latch lug 19. The workman, desiring to release the latch mechanism and open the elevator, reaches under the guard wall 52 and pulls the lever portion 47 of the lock lever 40 toward him. The force thereby applied to the lock lever 40 rotates the same in clockwise direction, against the force of the spring 45, into the position indicated by dotted lines 40a wherein the leftward edge of the arcuate wall 41 engages the front face of the latch lever 26 and the locking shoulder 50 of the lock lever 40 is moved leftwardly out of engagement with the lock lug 51. Thereafter, the pull which the workman exerts on the handle portion 47 of the lock lever 40 acts upon the latch lever 26 to swing the same in clockwise direction, thereby carrying the latching face 30 of the bar 29 out of engagement with the latching face 20 of the latch lug 19, whereupon the jaws 11 and 12 of the elevator will swing open.

When the elevator is in open position, counterclockwise rotation of the latch lever 26 is limited

by a shoulder 58 of the jaw 12, so that the latch lever 26 is maintained in position for reengagement with the latch lug 19 when the elevator jaws 11 and 12 are again swung into closed relation. The swinging of the jaws 11 and 12 is accomplished by use of handles 60 and 61 which project forwardly from the jaws 11 and 12 and have knobs 62 and 63 thereon for manual engagement. The reengagement of the parts of the latch mechanism is accomplished merely by moving the jaws 11 and 12 into closed relation, for the reason that the latch lug 19 and the bar 29 of the latch lever 26 have respectively angularly disposed faces 64 and 65 so that the bar 29 will ride over the lug 19 and then drop into latching position, whereupon the locking shoulder 50 of the lock lug 40 will move behind the lock lug 51.

One of the features of the latch and lock arrangement of the invention arises from the fact that the lock lever 40 projects forwardly from the latch lever, so that the latch lever 26 and the lock lever 40 define vertical planes which cross each other at an angle of substantially 90°. This gives a cooperation of parts in the structure wherein inertia or momentum acting in the structure in a direction to cause release of the latch lever 26 will not produce a release of the lock lever 40, and inertia or momentum acting in the structure in a direction to cause release of the lock lever 40 will not have such direction as to cause release of the latch lever 26. In explanation of this, let it be presumed that inertia is acting forwardly or along the line a—a from the hinge pin 14 through the latch lever 26. This exertion of the force of inertia in the latch lever 26 will tend to swing it in clockwise direction, but the same inertia acting in the lock lever 40 will tend to hold it in locked position or at least will not move the lock lever 40 out of its locked position. Likewise, inertia acting leftwardly through the center of gravity of the lock lever 40 so as to tend to swing the same in clockwise direction and unlock the same, will act longitudinally through the latch lever 26 and therefore will exert substantially no opening force on the latch lever 26.

I claim as my invention:

1. In a latch for an elevator comprising a pipe encircling structure with first and second free ends adapted to be latched together when the structure encircles the pipe, the combination of: a latch lug and a lock lug respectively carried by said first free end, both of said lugs being outwardly spaced from their associated end of the structure, with the lock lug spaced a greater distance than the latch lug; a latch lever hinged on said second free end for engaging said latch lug when said structure encircles said pipe; spring means urging said latch lever into a position for engagement with said latch lug; a lock lever on the outer face of said latch lever and positioned so that when said latch lever is in latching engagement with said latch lug, said lock lever will be positioned for locking engagement with said lock lug; means for urging said lock lever into engagement with said lock lug; manually engageable means carried by said lock lever for receiving a force which will swing said lock lever out of engagement with said lock lug and said latch lever out of engagement with said latch lug; and a wall extending from said first free end in a position to guard said manually engageable means.

2. In a latch for an elevator comprising a pipe

encircling structure with first and second free ends adapted to be latched together when the structure encircles the pipe, the combination of: a latch lug carried by one of said free ends; a latch lever pivotally carried by the other of said free ends for latchingly engaging the latch lug, when said structure encircles said pipe; means resiliently urging said latch lever toward latching position; a fixed separate lock lug carried by said one of said free ends positioned outwardly of said latch lug and beyond the latched position of said latch lever; a pivotally mounted lock lever carried by said latch lever adjacent its free end; means resiliently urging said lock lever to a locking position between the lock lug and the latch lever upon movement of the latter to latched position, whereby forces tending to move the latch lever from latched position act to put the lock lever in compression; and manually operable means for actuating said lock lever to release position.

3. In a latch for an elevator comprising a pipe encircling structure with first and second free ends adapted to be latched together when the structure encircles the pipe, the combination of: a latch lug carried by one of said free ends; a latch lever pivotally carried by the other of said free ends for latchingly engaging the latch lug, when said structure encircles said pipe; means resiliently urging said latch lever toward latching position; a fixed separate lock lug car-

ried by said one of said free ends positioned outwardly of said latch lug and beyond the latched position of said latch lever; a lock lever having an elongate portion spanning the free end of said latch lever and terminating in laterally projecting end lugs; means pivotally connecting said end lugs to adjacent parts of the latch lever for pivotal swinging movement; means resiliently urging said lock lever to a locking position between the lock lug and the latch lever upon movement of the latter to latched position, whereby forces tending to move the latch lever from latched position act to put the lock lever in compression; and a hand grip projection extending from the elongate portion of the lock lever in substantially parallel relation to the front face of the latch lever, inwardly of the outer end of said lock lug, for swinging said lock lever to release position.

WILLIAM WEBSTER WILSON.
